LENS HOUSING FOR AUTOMOBILE LAMPS

Carl W. Hood, Detroit, Mich., assignor to Chrysler Corporation, Highland Park, Mich., a corporation of Delaware

Application May 20, 1950, Serial No. 10,060

Term of patent 7 years

(Cl. D48—32)

To all whom it may concern:

Be it known that I, Carl W. Hood, a citizen of the United States, residing in the city of Detroit, county of Wayne, and State of Michigan, have invented a new, original, and ornamental Design for a Lens Housing for Automobile Lamps, of which the following is a specification, reference being had to the accompanying drawing, forming part hereof, in which:

Fig. 1 is a front elevational view of a lens housing for automobile lamps showing my new design;

Fig. 2 is a side elevational view thereof;

Fig. 3 is an elevational view showing the side opposite to Fig. 2; and

Figs. 4 and 5 are cross sectional views taken on the lines 4—4 and 5—5, respectively, of Fig. 1.

I claim:

The ornamental design for a lens housing for automobile lamps, substantially as shown.

CARL W. HOOD.
